CLAIM

The ornamental design for a weight training and exercise machine, as shown and described.

DESCRIPTION

FIG. 1 is a front and right side perspective view of a weight training and exercise machine showing my new design;

FIG. 2 is a rear and right side perspective view thereof;

FIG. 3 is a rear elevational view thereof;

FIG. 4 is a top plan view thereof;

FIG. 5 is a front elevational view thereof;

FIG. 6 is a right side elevational view thereof;

FIG. 7 is a left side elevational view thereof;

FIG. 8 is a bottom plan view thereof;

FIG. 9 is a rear perspective view thereof, with the hook members in an alternate position;

FIG. 10 is a front perspective view of FIG. 9; and,

FIG. 11 is a reduced rear elevational view thereof, shown with the ropes in an extended position.

*Fig. 1.**Fig. 2.**Fig. 3.**Fig. 4.**Fig. 5.**Fig. 6.**Fig. 7.**Fig. 8.**Fig. 9.**Fig. 10.**Fig. 11.*
